UNITED STATES PATENT OFFICE.

HUBERT KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

KEY-CONTROLLED DEVICE.

1,292,485.

Specification of Letters Patent.

Patented Jan. 28, 1919.

Application filed January 18, 1917. Serial No. 143,064.

To all whom it may concern:

Be it known that I, HUBERT KRANTZ, residing at Brooklyn, in the county of Kings and State of New York, have invented certain new and useful Improvements in Key-Controlled Devices, of which the following is a specification.

This invention relates to a key controlled device and is in certain part a division of 10 my copending application Serial No. 89,350, filed April 6, 1916.

While the device is primarily intended for use in connection with electric circuits it nevertheless may be applied to other uses 15 as will be apparent.

More particularly the invention relates to a device whereby an arm, such for instance as a switch arm, may be thrown from one position to another by the use of a key of 20 predetermined shape and size, and which device will include means for positively and firmly retaining the arm in its swung position, and which will at the same time, through a subsequent use of the key, cause 25 the arm to bound quickly away from its swung position.

The particular object of the invention is to provide this device in such a simplified, practical and efficient form as to be adaptable for use in various connections, and such that it may be dispensed as an article of manufacture irrespective of the particular use to which it may be applied.

Other objects and aims of the invention, 35 more or less specific than those referred to above, will be in part obvious and in part pointed out in the course of the following description of the elements, combinations, arrangements of parts and applications of 40 principles constituting the invention; and the scope of protection contemplated will be indicated in the appended claims.

In the accompanying drawings which are to be taken as a part of this specification, 45 and in which I have shown merely a preferred form of embodiment of the invention:

Figure 1 is a vertical sectional view through a device constructed in accordance with this invention, parts being broken away 50 and illustrated in section for better disclosing the structural arrangements.

Fig. 2 is a vertical sectional view taken upon the plane of line II—II of Fig. 1, 55 looking in the direction of the arrow; and Fig. 3 is a horizontal sectional view taken

upon the plane of line III—III of Fig. 1, looking in the direction of the arrow.

Referring to the drawing for describing in detail the structure which is illustrated therein, the reference character L indicates 60 the swinging arm. This is pivotally mounted as at 1 in suitable apertures formed through the opposite side members 2 and 3 of a rectangular supporting frame G.

The swinging or free end of this arm may 65 be adapted for any mechanical or electrical function, but preferably, for use as an electric switch, it carries a spring or laminated contact member 4 adapted for making electrical engagement with a pair of contact 70 plates such as those illustrated at 5 and 6.

The plates 5 and 6 may be supported in any desired manner not forming a part of this invention.

The contact member 4 is preferably insulated from the material of the arm L in any suitable manner, as for instance by the insulating sections 7 and 8.

In order to actuate the arm L a bell-crank lever 9 is provided, the same being pivotally 80 mounted within the frame G upon a pivot rod 10 extending between the plates 2 and 3. The space as 11 between the arms 12 and 13 of the bell-crank is utilized for receiving the operating portion of the key 34, as will 85 be readily understood from an inspection of Fig. 1. Pressure of the key against the surface 14 will swing the bell-crank in one direction, while pressure of the key against the surface 15 will swing the bell-crank in 90 a reverse direction.

The free end of the arm 12 of the bell-crank is pivotally connected by a pair of links 16 with the arm L. Preferably the links are arranged one at each side of the 95 arm 12 and are received within opposite recesses 17 formed in the sides of the arm L, the links being pivotally connected to the bell-crank by a pivot pin 18 and being pivotally connected to the arm L by a pivot 100 pin 19, as clearly indicated. The links 16, together with the arm 12 of the bell-crank constitute a toggle which is moved to a straightened position by swinging the key in one direction against the surface 14 of the 105 bell-crank, and which is moved to broken position by swinging the key against the surface 15 of the bell-crank. A transverse pin 20 extends between the plates 2 and 3 of the frame G in a position to constitute 110

an abutment to be engaged by the toggle when the toggle is in its straightened position. It is so arranged as to permit the toggle to move slightly beyond straightened position so that the toggle becomes automatically locked. This pin serves also as an abutment for limiting the movement of the arm L when the toggle is broken.

A compression coil spring H is arranged 10 in a position between one of the end walls 21 and a part of the arm L so as to exert a continuous pressure against the arm urging it into a position to break the toggle. This spring is held against displacement 15 preferably by having its opposite ends telescoped over lugs 22 and 23 formed respectively upon the wall 21 and the arm L. The lug 22 is shown to be arranged within a cut-away, or recessed portion of the wall 21. 20 This arrangement disposes a shoulder as 24 against which the adjacent end of the spring rests at a point spaced farther away from the arm L than the normal interior surface as 25 of the wall, thus providing for an increased length, and correspondingly improved resiliency, in the spring and at the same time affording a desirable thickness for the greater part of the length of the wall. The thickness of the wall is important in 30 that it lends rigidity to the structure. It may be added that the distance from the arm L to the outer surface of the wall is in many cases positively limited.

The lug 23 at the opposite end of the spring 35 is shown to constitute the head of a rivet as 26 which extends through the material of the arm L to the inner surface of the arm. The inner end of the rivet is formed up as at 27 to provide an appropriate hammer disposed for striking the abutment or pin 20 at each operation of the device. This detail of construction is important in that the blows struck against the abutment 20 are of some severity and, being oft repeated, would 40 injure the arm L. By the use of the separately formed rivet it is apparent that the same may be removed and renewed when desired.

In order to facilitate the easy introduction 50 of the key into the keyhole 28, a flared, or funnel-like escutcheon 29, is fixed to the outer surface of one of the plates, preferably the plate 3, as indicated.

Although any suitable means may be provided for attaching this device in association with other parts with which it is intended to coöperate, the drawing illustrates such attaching means as constituting lateral extensions 30 formed at the inner ends of 60 the plates 2 and 3 and projecting away from each other to provide flanges through which screws or other fastening elements may be driven. Preferably a broad thick wall, as 31, is arranged between the plates 2 and 3 65 at their inner ends. The plates may be

fixed to this wall and also to the wall 21 in any preferred manner, but they are usually connected by rivets as 32.

The pivot members 1 and 10, and also, if desired, the pin 20, are preferably made 70 detachable, being normally retained in position as by cotter pins 33, or the like. By withdrawing these members the arm L with the toggle mechanism may be bodily removed from within the casing for repairs 75 or otherwise.

The pivot members 18 and 19 are without heads and may, therefore, be readily withdrawn when the parts are removed from the casing. While the parts are in operative 80 position within the casing, the side plates 2 and 3 serve to retain the members 18 and 19 against accidental displacement.

The labor and expense for assembling, both during manufacture and subsequently, 85 is materially reduced, without in any way affecting the uniformly efficient character and durability of the structure.

As many changes could be made in this construction without departing from the 90 scope of the following claims, it is intended that all matter contained in the above description or shown in the accompanying drawing shall be interpreted as illustrative only and not in a limiting sense. 95

Having thus described my invention what I claim as new and desire to secure by Letters Patent is:

1. In a device of the class described, a pivotally mounted arm arranged to swing 100 into two positions, means urging the arm toward one of its positions, and key-controlled means for controlling and counter-acting the effects of said means at will.

2. In a device of the class described, a 105 pivotally mounted arm arranged to swing into two positions, a resilient member urging the arm toward one of its positions, and key-controlled means for swinging said arm against the tendency of said resilient member. 110

3. In a device of the class described, a pivotally mounted arm arranged to swing into two positions, a resilient member urging the arm toward one of its positions, and 115 key-controlled means for swinging said arm against the tendency of said resilient member, said means comprising parts adapted to lock the arm against the tendency of the resilient member.

4. In a device of the class described, a pivotally mounted arm arranged to swing into two positions, a spring urging the arm toward one of its positions, and key-controlled toggle mechanism connected with 120 said arm for swinging said arm against the tendency of the spring and for locking the arm against the tendency of the spring.

5. In a device of the class described, a pivotally mounted arm arranged to swing 125

into two positions, a spring urging the arm toward one of its positions, a pivotally mounted key-controlled bell-crank member, and a link connecting one arm of said bell-crank member with said first mentioned arm adapted to coöperate with the arm of the bell-crank member to provide a toggle whereby the key-operated movements of the bell-crank member will swing the first mentioned arm against the tendency of the spring.

6. In a device of the class described, a pivotally mounted arm arranged to swing into two positions, a spring urging the arm toward one of its positions, an abutment for arresting movement of the arm in its last mentioned direction, a toggle for moving the arm away from said abutment, said abutment serving also as limiting means for limiting movement of the toggle to lock the toggle in straightened condition, and means whereby the toggle is key-controlled.

7. A device of the class described, comprising a supporting frame made up of a pair of plates spaced apart and an end wall member between said plates to which said plates are rigidly connected, an arm arranged between said plates being pivotally mounted to swing from a backward to a forward position, a spring interposed between said arm and said end wall member for urging the arm to its backward position, a pin extending between said plates comprising an abutment for arresting the backward movement of the arm, toggle mechanism arranged between said plates being supported partly by said plates and partly by said arm, a key, and one of said plates having a keyhole formed therethrough through which a key may be inserted into engagement with said toggle for operating the toggle to swing the arm to its forward position.

8. A device of the class described, comprising a supporting frame made up of a pair of plates spaced apart and an end wall member between said plates to which said plates are rigidly connected, an arm arranged between said plates being pivotally mounted to swing from a backward to a forward position, a spring interposed between said arm and said end wall member for urging the arm to its backward position, a pin extending between said plates comprising an abutment for arresting the backward movement of the arm, toggle mechanism arranged between said plates being supported partly by said plates and partly by said arm, a key, one of said plates having a keyhole formed therethrough through which a key may be inserted into engagement with said toggle for operating the toggle to swing the arm to its forward position, and said mentioned pin constituting also an abutment for arresting movement of the toggle to lock the toggle in position with the arm swung forward.

9. A device of the class described, comprising a supporting frame made up of a pair of plates spaced apart and an end wall member between said plates to which said plates are rigidly connected, an arm arranged between said plates being pivotally mounted to swing from a backward to a forward position, a spring interposed between said arm and said end wall member for urging the arm to its backward position, an abutment for arresting the backward movement of the arm, key-controlled means for moving the arm against the tendency of the spring, and means for retaining the spring in engagement with the arm comprising a member over which a part of the spring telescopes, said member having also a part disposed to serve as a hammer for engaging said abutment.

10. A device of the class described, comprising a supporting frame made up of a pair of plates spaced apart and an end wall member between said plates to which said plates are rigidly connected, an arm arranged between said plates being pivotally mounted to swing from a backward to a forward position, a spring interposed between said arm and said end wall member for urging the arm to its backward position, said arm being of a thickness to be received loosely between said plates and having a pair of recesses formed in its opposite side surfaces, a pair of links one extending into each of said recesses being pivotally connected to said arm, another link pivotally connected by one of its ends between the outer ends of said pair of links, means pivotally connecting the remaining end of said last mentioned link to said plates whereby all of said links constitute a toggle received compactly between said plates and adapted to swing the arm against the tendency of the spring, and one of said links having a key receiving part whereby to render the toggle key-controlled.

11. A device of the class described, comprising a supporting frame made up of a pair of plates spaced apart and an end wall member between said plates to which said plates are rigidly connected, an arm arranged between said plates being pivotally mounted to swing from a backward to a forward position, a spring interposed between said arm and one of said end walls for urging the arm to its backward position, means for urging the arm against the tendency of the spring, said mentioned end wall having a recess formed in its inner surface to receive the adjacent end of the spring whereby to permit of the use of an increased length of spring, and a lug projecting from said recess about which said spring telescopes to retain the spring in said recess.

12. A device of the class described comprising a frame made up of a pair of plates

4
spaced apart, a switch arm pivotally supported between said plates, a pivot shaft extending between said plates by which said switch arm is supported, resilient means engaging said switch arm and a part of said frame removed from said pivot shaft to urge the switch arm in one direction, means by which to operate the switch arm against said resilient means, and at least one of said plates having a laterally extending projection formed thereon to constitute attaching means for the device.

13. A device of the class described, comprising a frame, a switch arm mounted by said frame, operating mechanism for the switch arm arranged between and protected by portions of said frame, and a double-ended switch blade carried by the projecting portion of said switch arm.

14. A device of the class described, comprising a frame, a switch arm pivotally mounted within said frame, operating mechanism for said switch arm also within said frame, a key, and a portion of said frame having a keyhole formed therethrough through which a key may be inserted for controlling said operating mechanism.

15. A switch mechanism combining a swinging switch blade, a toggle for positioning the same, and a detachable key for actuating said toggle.

16. A device of the class described, comprising a supporting frame having spaced side wall parts and a connecting wall part, an arm arranged between the side wall parts being pivotally mounted to swing into two positions, a spring interposed between said arm and said connecting wall part for urging the arm into one of its positions, a pin extending between the side wall parts comprising an abutment for arresting the spring pressed movement of the arm, toggle mechanism arranged between said side wall parts partly supported directly thereby and partly supported by said arm, and one of said side wall parts having a key-hole formed therethrough through which a key may be inserted into engagement with said toggle for operating the toggle to swing the arm into its other position.

17. A key-controlled switch comprising a switch blade, operating means to operate the switch blade, a plurality of protecting wall members between which said switch blade and said operating means are arranged and protected, one of said wall parts having a

keyhole formed therethrough, and a key having a portion adapted to be inserted through said key-hole into position between said protecting walls for engaging and operating said switch operating means.

18. In a switch mechanism, a movable switch blade, a toggle for moving the switch blade, a key for controlling the toggle, one member of the toggle having parts providing spaced shoulders thereon to be engaged by the actuating portion of the key in accordance with the direction of movement of the key to make and break the toggle, and the actuating portion of the key being of such proportion relative to the distance between said shoulders that when it presses against one shoulder to the point of breaking the toggle the actuating portion of the key will have assumed a position entirely clear of the extreme broken position of the second shoulder.

19. A switch mechanism comprising a supporting frame made up of a pair of side wall parts spaced apart and a connecting wall part, a switch blade disposed between said side wall parts, being pivotally mounted thereupon and having a contact portion projecting outwardly from between said side wall parts, resilient means also between said side wall parts engaging said switch blade to normally retain the switch blade "off", and means also arranged between said side wall parts operable to swing the switch blade into "on" position at will.

20. A switch mechanism comprising a supporting frame made up of a pair of side wall parts spaced apart and a connecting wall part, a switch blade disposed between said side wall parts, being pivotally mounted thereupon and having a contact portion projecting outwardly from between said side wall parts, resilient means also between said side wall parts engaging said switch blade to normally retain the switch blade "off", and means also arranged between said side wall parts operable to swing the switch blade into "on" position at will, together with a key adapted to be inserted into position between said side wall parts for operating the last mentioned means.

In testimony whereof I affix my signature in the presence of two witnesses.

HUBERT KRANTZ.
